US0D1040787S

(12) **United States Design Patent** (10) **Patent No.:** **US D1,040,787 S**
(45) **Date of Patent:** **** Sep. 3, 2024**

(54) **EARPHONE**

(71) Applicant: **SHENZHEN EMEET TECHNOLOGY CO., LTD.**, Shenzhen (CN)

(72) Inventor: **Wenming Chen**, Guangdong (CN)

(**) Term: **15 Years**

(21) Appl. No.: **35/518,783**

(22) Filed: **Aug. 9, 2023**

(80) **Hague Agreement Data**

Int. Filing Date: **Aug. 9, 2023**

Int. Reg. No.: **DM/231511**

Int. Reg. Date: **Aug. 9, 2023**

Int. Reg. Pub. Date: **Oct. 27, 2023**

(51) **LOC (14) Cl.** **14-01**

(52) **U.S. Cl.**

USPC **D14/223**

(58) **Field of Classification Search**

USPC ... D14/205, 207, 209, 209.1, 217, 221, 223, D14/225; D24/106, 173, 174; D29/112
